UNITED STATES PATENT OFFICE.

ELISHA W. CROCKER, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

CAN-END-SECURING MACHINE.

1,316,083.

Specification of Letters Patent. Patented Sept. 16, 1919.

Application filed September 9, 1918. Serial No. 253,235.

To all whom it may concern:

Be it known that I, ELISHA W. CROCKER, a citizen of the United States, residing at Providence, in the county of Providence and State of Rhode Island, have invented a new and useful Improvement in Can-End-Securing Machines, of which the following is a specification.

This invention relates to certain new and useful improvements in can end securing machines and pertains more particularly to a machine for securing the bottoms or tops of cans or containers to the cylindrical can bodies.

15 The invention has for its object to produce a machine of this type in which the operator by successive and practically continuous movement of a single tool carrier can easily and expeditiously effect the successive operations or steps so as to secure the can top or bottom to the container body.

A further object of the invention is to provide a machine of this character which is of simple and economical construction and 25 in which there are a minimum of parts which are compactly related.

Further and other objects will be later set forth and of themselves manifested in the course of the following description.

30 In the drawings—

Figure 1 is a top plan view partly broken away.

Fig. 2 is an end elevation.

Fig. 3 is a section on the line 3—3 of 35 Fig. 1.

Fig. 4 is a side elevation showing the can and an end thereto in section and the tucker mechanism in the act of performing its function.

40 Fig. 5 is a fragmentary view showing the can body and an end thereto assembled on the can carrier and ready for the first step of the securing or bending operation.

Fig. 6 is a similar view showing the parts 45 in the second step and the tool for effecting the latter.

Fig. 7 is a view similar to Fig. 6 showing the parts in the second step of the operation.

Fig. 8 is a similar view showing the parts 50 in the third step of the operation.

Fig. 9 is a similar view showing the parts in the fourth step of the operation, and

Fig. 10 is a view showing the parts in the final or finished step of the operation.

55 In proceeding in accordance with the in-

vention, a can carrier 1 is employed which latter is rotated at a relatively high speed by any means (not shown). The carrier is formed to provide a raised support or bed 2 for the can top, bottom or end B and has a 60 smooth peripheral portion 3 of somewhat disk like formation so as to leave annular space 4 between the disk 3 and the base of the carrier 1 as depicted in the drawings, so that the flange F of bottom B will, when the 65 latter is placed on the raised bed 2 of the carrier overhang the base of the latter and be disposed in the plane of the bottom face of the disk 3.

Arranged on one side of the carrier 1 is a 70 tool carrier 5 which is mounted for free rotation on a suitable post 6. The tool carrier consists of a pair of superposed spaced disks 8 and 7 held in their spaced relation by a collar or washer 9 surrounding the reduced upper end 10 of the post 6, the end 10 forming a stub shaft about which the disks 7 and 8 rotate and also a shoulder 11 on which the disk 8 seats. The cap plate 12 and screw 13 are employed to secure the tool carrier 5 on the stub shaft 10. The tools are in the form of wheels and are mounted on bolts 14 which extend through aligned perforations in the disks 7 and 8 and are secured in position by the nuts 15.

Referring to Fig. 1 it will be seen that the tool carrier 5 has five wheels thereon arranged in the successive order now to be described. Wheel 16 has a circular flange 17 of uniform thickness and a smooth peripheral portion 18 which projects upwardly from the flange 17, the thickness of the flange 17 being sufficient so as to admit the latter in the space 4 of the can carrier 1 as depicted in Fig. 6. Wheel 19 has a flange 20 similar to flange 17 and an upwardly projecting portion 21 which is provided with a downwardly converging peripheral part 22. The next wheel 23 has a circular flange 24 and an upwardly extending part 25 formed with a groove 26 that is of concave outline. The next wheel 27 has a flange 28 and an upwardly projecting part 29 formed with an outwardly flared or converged peripheral part 30, while the last wheel 31 has a circular flange 32 and an upwardly projecting circular part 33 formed with a concave groove 34 similar to groove 26 but of greater width than the latter.

The tucker wheel 35 is provided with a 110

circular part having a concave peripheral groove 36, the tucker wheel being rotatably mounted on one end of a curved arm 37 which latter is pivoted at 38 to the outer end 5 of a substantially vertical arm 39. Arm 39 is pivoted at 40 to the bracket 41 which latter is carried by a member 42 suitably secured to the frame of the machine. The tool carrier 5 is formed with a radial per-
10 foration in which is secured a rod 43 providing a handle so that the operator may turn the tool carrier 5 in a manner later described. The tool carrier 5 is pivoted to the bracket 41 as shown in Fig. 2.
15 In operation the body of the can C and an end thereof B is furnished from the press as shown in Fig. 5, the parts being placed on the carrier 1 and clamped to the portion 3 thereof as shown in Fig. 5. The car-
20 rier 1 is now caused to rotate at a high speed, the operator next grasping handle 43 so as to turn the carrier 5 to bring the wheel 16 into operation, the peripheral part 18 of the wheel 16 engaging the flared edge F of
25 the bottom B as shown in Fig. 6 so as to move said edge F inwardly to be turned into the upright position of Fig. 6. It will be noted that in this step as well as in all of the succeeding steps the flanges 17, 20, 24,
30 28, and 32 have their upper faces providing supports engaging the flange F of the can bottom B, so as to prevent downward movement of the can C or the end B thereof. After the parts have been rolled into the po-
35 sition of Fig. 6, the operator then turns the carrier 5 to bring wheel 19 into operation. The flared part 22 or wheel 19 bends the flange F of bottom B inwardly by contact with the inclined part 2 as depicted in Fig.
40 7. The operator now again turns carrier 5 bringing the wheel 23 into operation the latter depressing the flange F as shown in Fig. 8 between the base of the part 25 of wheel 23 and the upper face of flange 24
45 thereof. Upon further turning of the car-
rier 5 by the operator wheel 27 is brought into operation, the upwardly flared peripheral portion 30 of which turns the flange F upwardly at an angle as depicted in Fig. 9.
50 In this operation the flange F of the bottom B sometimes will spring outwardly or next to the can body C. In such cases the tucker wheel 35 is brought into operation by lifting the arm 37 into the position of Fig. 4 until
55 the outer face of the tucker wheel 35 contacts with a periphery of the can body C, further lifting of the arm 37 causing depression of the wheel 35 and contact with the flange of the bottom B so as to bend same in
60 place as shown in Fig. 4. The finishing wheel 31 is now brought into operation rolling the two flanges, *i. e.*, F and G into intimate contact so as to make an air tight re-
65 lationship of the parts as shown in Fig. 10. The wheel 31 can obviously be of any de-

sired configuration so as to give the parts any desired final shape other than that shown in Fig. 10. The peripheral part 34 of wheel 31 could also be knurled so as to knurl the bead at its periphery. Since the 70 carrier 5 is given a practically uninterrupted movement by the operator, the operation is practically one continuous motion of the handle or rod 13.

By referring to Fig. 4 it will be apparent 75 that the tucker wheel 35 has a compound mechanism, namely, it can move vertically in both directions as well as horizontally toward and away from the can. It will furthermore be apparent that the tucker 80 mechanism is selectively operable and when operated its point of operation is in advance of the crimping wheels so as to not interfere with the latter in any way whatsoever. It will furthermore be noted that the parts 85 could be positioned with the carriers 1 and 5 vertical, instead of horizontal, as shown.

Having thus described my invention, what I claim as new and desire to secure by Letters Patent is—

1. In a machine for securing can ends to the bodies thereof, a can carrier, a rotatable tool carrier adjacent thereto, means to rotate the tool carrier, a series of wheels rotatably carried by the tool carrier for successive engagement with the flanges of the can body and end to bend said flanges into interlocking engagement, an arm, means to pivotally support the arm, a second arm pivoted to an end of the first arm, and a 100 tucker wheel mounted on the free end of the second arm.

2. In a machine for securing can ends to the bodies thereof, a can carrier, a tool car-
105 rier, crimping means on the tool carrier, a substantially vertical arm, means to pivotally support said arm from the lower end thereof to allow same to swing bodily into and out of the plane of the can carrier, a second arm traversing the upper end of the 110 vertical arm and pivoted at an intermediate point to the vertical arm so as to lie in one position above the pivotal point of the vertical arm, a tucker wheel carried by the front end of the second arm, and a handle 115 on the rear end of the second arm.

3. In a machine for securing can ends to the bodies thereof, a can carrier, seaming means, a pivoted element movable toward and away from the seaming means, a second 120 element pivoted to the first element so as to move with the first element and also inde-
pendently of the first element, a tucker wheel carried by an end of the second ele-
ment, and a handle on the second element to 125 move both elements in unison or the second element independent of the first element.

4. In a machine for securing can ends to the bodies thereof, a can carrier, seaming means, an element pivoted at one end so as 130

to be bodily swingable toward and away from the seaming means, a second element pivoted between its ends to the opposite end of the first element, and having a free end, and a tucker wheel carried by the free end of the second element, the opposite end of the second element forming a handle whereby to oscillate the second element relative to the first element, or to move both elements in unison.

5. In a machine for securing can ends to the bodies thereof, a can carrier, a tool carrier, crimping means on the tool carrier, an

arm, means to pivot said arm to allow an end thereof to swing into and out of the plane of the can carrier, a second arm, means to pivotally connect the second arm to said end of the first arm, and a tucker wheel on an end of said second arm.

15 In testimony whereof I have signed my name to this specification in the presence of two subscribing witnesses.

ELISHA W. CROCKER.
